[57] **CLAIM**

The ornamental design for a combined bottle neck clamp and tube holder, as shown and described.

DESCRIPTION

FIG. 1 is a perspective view of a combined bottle neck clamp and tube holder showing my new design;

FIG. 2 is a top plan view thereof;

FIG. 3 is a bottom view thereof;

FIG. 4 is a right side elevational view thereof, the opposite side being substantially identical;

FIG. 5 is a front elevational view thereof; and,

FIG. 6 is a rear elevational view thereof.

FIG. 1.FIG. 2.FIG. 3.FIG. 4.FIG. 5.FIG. 6.
